DESIGN FOR A PORTABLE AUTOGRAPHIC
REGISTER

Walter D. Teague, Annandale, N. J., assignor to
Moore Business Forms, Inc., Niagara Falls,
N. Y., a corporation of Delaware

Application June 15, 1946, Serial No. 130,761

Term of patent 14 years

(Cl. D74—1)

To all whom it may concern:

Be it known that I, Walter D. Teague, a citizen of the United States, residing at Annandale, in the county of Hunterdon and State of New Jersey, have invented a new, original, and ornamental Design for Portable Autographic Registers, of which the following is a specification, reference being had to the accompanying drawing, forming part thereof, and in which:

Fig. 1 is a front perspective view of a portable autographic register showing my new design;

Fig. 2 is an enlarged front end elevation thereof;

Fig. 3 is an enlarged elevation of the left side thereof; and

Fig. 4 is an enlarged rear elevation.

I claim:

The ornamental design for a portable autographic register, as shown and described.

WALTER D. TEAGUE.
